(57) **CLAIM**

The ornamental design for folder, as shown and described.

DESCRIPTION

FIG. 1 is a front perspective view of a first embodiment of a folder showing my new design;

FIG. 2 is a front elevational view thereof;

FIG. 3 is a right side elevational view thereof, the left side elevational view being a mirror image thereof;

FIG. 4 is a top plan view thereof;

FIG. 5 is a bottom plan view thereof;

FIG. 6 is a front perspective view of a second embodiment of a folder showing my new design;

FIG. 7 is a front elevational view thereof;

FIG. 8 is a left side elevational view thereof;

FIG. 9 is a right side elevational view thereof;

FIG. 10 is a top plan view thereof;

FIG. 11 is a bottom plan view thereof;

FIG. 12 is a front perspective view of a third embodiment of a folder showing my new design;

FIG. 13 is a front elevational view thereof;

FIG. 14 is a right side elevational view thereof, the left side elevational view being a mirror image thereof;

FIG. 15 is a top plan view thereof;

FIG. 16 is a bottom plan view thereof;

FIG. 17 is a front perspective view of a fourth embodiment of a folder showing my new design;

FIG. 18 is a front elevational view thereof;

FIG. 19 is a left side elevational view thereof;

FIG. 20 is a right side elevational view thereof;

FIG. 21 is a top plan view thereof; and,

FIG. 22 is a bottom plan view thereof.
